FIG. 1

FIG. 2

FIG. 3

FIG. 5

FIG. 4

FIG. 1 is a side elevational view of a power operated tool showing my new design; the opposite side is the same; FIG. 2 is a top plan view thereof;

FIG. 3 is a bottom plan view thereof;

FIG. 4 is a rear end view thereof; and

FIG. 5 is a front end view thereof.

The dotted line showing of a chuck in FIG. 1 is for illustrative purposes only since it is not an actual part of the design.

I claim:

The ornamental design for a power operated tool, as shown and described.
